UNITED STATES PATENT OFFICE.

JOSEPH H. CAMPBELL, OF NEW YORK, N. Y.

METHOD OF UTILIZING AQUA-AMMONIA AS A MOTIVE POWER IN ENGINES.

SPECIFICATION forming part of Letters Patent No. 399,131, dated March 5, 1889.

Application filed September 19, 1887. Renewed July 24, 1888. Serial No. 280,917. (No model.)

To all whom it may concern:

Be it known that I, JOSEPH H. CAMPBELL, a citizen of the United States of America, residing at New York, in the county of New 5 York and State of New York, have invented certain new and useful Improvements in the Method of Utilizing Aqua-Ammonia as a Motive Power in Engines, of which the following is a specification, reference being had therein 10 to the accompanying drawing.

My invention relates to improvements in the method and apparatus for utilizing aqua-ammonia as a motive power in engines.

The object of my present invention is, in 15 operating an aqua-ammonia engine, to return the exhaust-vapor and the solution used in spraying the exhaust to the boiler by means of a vapor-pump—viz., a pump driven by the vapor of ammonia—which is similar in construction to the ordinary steam-pump used for like purposes, and is intended as an improvement on my method described in my patents, Nos. 337,371, 337,372, 337,373, 337,374, of March 9, 1886, and No. 346,425, of July 27, 20 1886, and application filed August 6, 1887, Serial No. 246,357.

A further object of my invention is to control the pressure of the vapor in the boiler, especially when the engine has been suddenly 25 stopped or the load so reduced that but little vapor is required to run the engine, by the aid of a pump adjusted, as hereinafter explained, whereby I avail myself of a continuous supply of liquid, which is drawn from the boiler, cooled, and returned as the emergency 30 requires, thus avoiding the storage of a large amount of liquid and accomplishing other results, as will be more fully explained herein-after.

40 The devices embraced in this invention perform nearly the same function as that of a safety or blow-off valve in a steam-engine.

My invention consists in the method, hereinafter described, of returning the exhaust of 45 the engine and the liquid used for spraying or absorbing said exhaust by means of a pump driven by ammonia-vapor, having its exhaust connected with the exhaust of the engine, or so constructed that the spray-liquid will come 50 in contact with the same.

My invention consists, further, in the method, hereinafter described, of relieving the boiler

of an excess of pressure by transferring the solution from the boiler to the absorbers, where it is cooled and returned to the well, ready 55 for use in the boiler.

My invention consists, further, in providing means for conveying vapor from the boiler to the absorbers without passing it through the engine.

My invention consists, further, in automatically increasing the amount of absorbing or spray liquid and of circulating water with the increase of the pressure in the boiler.

For the purpose of illustrating my invention, I have shown in the drawing a longitudinal view, partly in section, of the boiler, engine, cooler, absorbers, pumps, pipes, and valves which constitute my machine, and such will be described hereinafter in detail.

A represents a boiler and E an engine, both of ordinary construction, the same being connected with each other by means of the vapor-pipe D.

O is the main exhaust-pipe for the engine, 75 and J a pipe for conveying liquid or weak solution in a continuous stream and under boiler-pressure from the boiler through the cooler T to the exhaust-pipe of the engine, and described as a spray-pipe in my patents 80 above mentioned.

S and S' are surface-condensers through which the combined exhaust-vapor and absorption liquid or spray are conveyed, and in which they are cooled on their way to the 85 well W.

P is a feed-pump constructed similar to ordinary steam-pumps, and is used for pumping the liquid from the well W to the boiler. Said pump obtains its supply of vapor for 90 propelling its piston from the main pipe D by means of the branch pipe d. Its exhaust-pipe e leads into the main exhaust-pipe O at a point, X, located between the engine E and the absorber S.

P' is a double pump receiving the vapor-supply from the main pipe D by means of the branch pipe d'. It is shown here to be provided with a central cylinder, c', which has a piston moving within propelled by the vapor 100 entering it through the pipe d'. The exhaust-vapor is discharged through the exhaust-pipe f' into the main exhaust-pipe O at y, so as to be absorbed by the spray j, which performs

the same function for the vapor that passes through the cylinder of the engine E. The piston-rod of the pump P' has attached to it a piston in the cylinder C² and another one in the cylinder C³.

5 a' is the suction-pipe for the cylinder C². The same may take its supply from any suitable source of cooling-water.

a^o is the discharge-pipe. The same enters 10 the cooling-pipe a' a', which furnishes a constant supply of water, and is shown here to lead to the cooling-chamber T, the water for cooling being from there conveyed through the pipes a² and a³ to the surface-condenser 15 S', and from there by the pipe a⁴ to the surface-condenser S, and finally discharged through the pipe a⁵. A branch pipe, a⁶, passes through the well W in the form of a coil, and the circulation of cooling-water through the 20 same can be interrupted by closing the cock v.

h' is the suction-pipe for the cylinder c², taking its supply from the liquid in the well W, and is provided with a valve, v².

N' is the discharge-pipe leading into the 25 vapor-space of the boiler A.

l² is a weighted valve constructed and adjusted to open automatically when a given pressure is reached above it in the pipe d'.

l' is a cock to enable the engineer to regulate 30 late the vapor-supply to the pump P' by hand.

Q is a pipe connecting the pipe O with the pipe J.

l³ is a weighted valve opening automatically under a given pressure, the cock l⁴ being then 35 open.

N N is a pipe connecting with the main vapor-pipe D, as well as with the exhaust-pipe O, and passing around the engine E it is provided with a cock, l⁵, which the engineer 40 may open or close at will, while l⁶ is an automatic valve adjusted to open when a given pressure is reached, the cock l⁵ then being open.

45 v³ is a cock or automatic valve to be closed when the excess of pressure in the boiler demands a larger supply of liquid to be injected in the vapor-space of the boiler through cylinder c³ and pipe h'.

The operation of the apparatus as shown is 50 as follows: The operation of the pump P is that of an ordinary steam-pump, except that the exhaust of this pump is returned to the boiler by the aid of the spray or absorbing liquid used for the cylinder of the main engine, it being found 55 in practice difficult to use an independent spray for the pump without using an orifice or nozzle so large that the economy of the plant would be materially affected. The amount of vapor required for the work to be 60 performed by pump P being small, it is not necessary to depend upon a spray or absorbing jet for the absorption of the exhaust-vapor, it being sufficient to bring it in contact with the fluid-exhaust in pipe O at X before 65 entering the absorbers S and S'.

The operation of the pump P' is as follows: Whenever there is an excess of pressure in

the boiler and pipes D and d', the cock l' being open, the weighted valve l² will be opened and will admit vapor to cylinder C, thus starting the pump P'. The excess of pressure will also open weighted valve l⁴, l³ being open at the time, thus permitting a larger supply of the liquid to pass from the boiler to the absorbers, when it will be cooled and by gravity will flow into the well W. The cock v³ being closed, the entire quantity of liquid thus drawn from the boiler and cooled will be withdrawn from the well W by means of pump P' and discharged through the pipe h⁸⁰ and spray-nozzle or rose-head n into the vapor-space of the boiler, where, being brought in contact with the vapor, it will absorb a portion of it, as well as reduce the temperature, thus reducing the pressure in the boiler. 85

The operation of the pipe N N, forming a by-pass around the engine E, is as follows: The cock V⁴ being closed and l⁵ being open, the vapor will pass directly from the pipe D to the exhaust-pipe O, where it is brought in 90 contact with the spray or absorbing liquid at j, by which it is absorbed, and, passing through the absorbers to the well, it will be returned to the boiler either by the pump P or P'. This operation may be rendered automatic by substituting for the cock l⁵ a valve, l⁶, weighted to the desired pressure. Ordinarily such valve l⁶ would have to be adjusted to open at a lower pressure than l², thus in case of a comparative- 95 ly slight rise in pressure doing away with the starting of the pump P'. For the purpose of obtaining an increased supply of cooling-water for the fluid thus forced through the pipes J and Q, the water-cylinder C² of the pump P' is operated, as heretofore described, so as to add 100 the water-supply passing through it when the pump P' is in motion to the supply of cooling-water ordinarily passing through a a. While both pumps P and P' may be used to force back into the boiler the fluid so cooled, it will 105 be seen that the fluid so introduced into the vapor-space will be more effective in promptly reducing the boiler-pressure, as it will come in direct contact with the vapor and will thus absorb it, while the fluid passed into the 110 boiler through P' below the fluid-line will only serve to reduce the general temperature of the 115 boiler and of the fluid in the same.

When the engineer desires to avail himself 120 exclusively of the pump P' for forcing fluid from the well W to the boiler, he can do so by closing valve V³ in the suction-pipe of pump P. I do not wish to limit myself in cooling the fluid passing through Q to the use of the apparatus provided for cooling the combined 125 spraying or absorbing fluid and exhaust-vapor represented in the drawing by the surface condensers or absorbers S and S' and the well W, as it will readily be seen that while it will ordinarily simplify the construction of the apparatus to do so a separate cooling apparatus might be provided for the fluid 130 passing through Q.

Having thus described my invention, what I

claim, and desire to secure by Letters Patent, is—

1. The method herein described of relieving the boiler of an aqua-ammonia engine from an excess of pressure, which consists in drawing off a portion of the solution or liquid from the boiler through an aperture additional to the exhaust-absorbing jet, cooling said solution, and returning it to the boiler, as set forth.
2. The method herein described of relieving the boiler of an aqua-ammonia engine from an excess of pressure, which consists in drawing off a portion of the solution or liquid from the boiler through an aperture additional to the exhaust-absorbing jet, cooling said solution, and returning it to the vapor-space of the boiler, where it is brought in contact with the vapor in the boiler, as set forth.
3. The method herein described of relieving the boiler of an aqua-ammonia engine from an excess of pressure, which consists in causing the pressure of vapor in the boiler to automatically start and operate a pump to transfer cool solution to the boiler, whereby the pressure is reduced by the introduction of the cooled solution or fluid into the boiler, as set forth.
4. The method herein described of operating a vapor-pump, in combination with an aqua-ammonia engine, which consists in driving a pump directly by vapor of aqua-ammonia and absorbing the exhaust-vapor of said pump by a continuous stream of absorbing-liquid designed to absorb the exhaust of the engine, substantially as set forth.
5. The method herein described of operating a vapor-pump, in combination with an aqua-ammonia engine, the same consisting in driving a pump directly by vapor of aqua-ammonia and absorbing the exhaust-vapor of said pump by the absorbing-liquid designed to absorb the exhaust of the engine, substantially as set forth.
6. The method herein described of utilizing a single-spray jet for absorbing the exhaust-vapor from an engine and a pump, the same

consisting in bringing the exhaust-pipes of said engine and pump into one common exhaust-pipe which is provided with an absorbing-jet, substantially as set forth.

7. The method herein described of relieving the boiler of an aqua-ammonia engine from an excess of pressure, which consists in transferring the vapor from the boiler directly to the absorbers and well without passing it through the engine and bringing said vapor in contact with a continuous stream under boiler-pressure of cooled weak solution or fluid while in transit to the absorbers, as set forth.

8. The method herein described of relieving the boiler of an aqua-ammonia engine from an excess of pressure, which consists in transferring the vapor from the boiler directly to the exhaust-pipe of the cylinder of the engine without passing it through the engine and bringing such vapor in contact with a continuous stream of the cooled weak solution, as set forth.

9. The method herein described of reducing the pressure in the boiler of an aqua-ammonia engine, which consists in conveying the vapor from the pipe leading from the boiler to the cylinder of the engine directly to the exhaust-pipe of the cylinder and absorbing said vapor, together with exhaust-vapor from the cylinder, by a continuous stream of the cooled solution, as set forth.

10. The method herein described of relieving the boiler of an aqua-ammonia engine of excessive pressure, which consists in withdrawing liquid from the boiler, cooling it by cooling-water, and returning the liquid to the boiler, part of said cooling-water being supplied by a pump started and operated by such excessive pressure, substantially as set forth.

In testimony whereof I affix my signature in presence of two witnesses.

JOSEPH H. CAMPBELL.
